UNITED STATES PATENT OFFICE

159,561

LAMP TABLE

George I. Tanier, New York, N. Y., assignor to
Alden Woodcrafts, Inc., Brooklyn, N. Y., a corporation of New York

Application June 24, 1948, Serial No. 147,171

Term of patent 3½ years

(Cl. D33—14)

To all whom it may concern:

Be it known that I, George I. Tanier, a citizen of the United States, residing at New York, in the county of New York and State of New York, have invented a new, original, and ornamental Design for a Lamp Table, of which the following is a specification, reference being had to the accompanying drawing, forming part thereof.

Fig. 1 is a front perspective view of a lamp table, showing my new design.

Fig. 2 is an end view of Fig. 1.

I claim:

The ornamental design for a lamp table, as shown.

GEORGE I. TANIER.
